(57) **CLAIM**

The ornamental design for a housing and keypad of a mobile computing device, as shown and described.

DESCRIPTION

FIG. 1 is a leftward front isometric view of a housing and keypad of a mobile computing device showing a first embodiment;

FIG. 2 is a rightward front isometric view thereof;

FIG. 3 is a front view thereof;

FIG. 4 is a partial enlarged leftward isometric view thereof;

FIG. 5 is a cross-sectional view along lines 5—5 of FIG. 4 thereof;

FIG. 6 is a cross-sectional view along lines 6—6 of FIG. 4 thereof;

FIG. 7 is a cross-sectional view along lines 7—7 of FIG. 4 thereof;

FIG. 8 is an isometric view showing embodiment 1 in use;

FIG. 9 is a front view of a second embodiment where the other views are identical to that of embodiment 1;

FIG. 10 is a front view of a third embodiment where the other views are identical to that of embodiment 1;

FIG. 11 is a front view of a fourth embodiment where the other views are identical to that of embodiment 1; and,

FIG. 12 is a front view of a fifth embodiment where the other views are identical to that of embodiment 1.

The portions of the mobile computing device shown in broken lines form no part of the claimed design.
